UNITED STATES PATENT OFFICE.

FRANK L. LINDSTROM, OF BRIDGEPORT, CONNECTICUT.

SPINNING TOP.

Application filed January 21, 1922. Serial No. 530,780.

To all whom it may concern:

Be it known that FRANK L. LINDSTROM, a citizen of the United States, and resident of Bridgeport, in the county of Fairfield and

5 State of Connecticut, has invented certain new and useful Improvements in Spinning Tops, of which the following is a specification.

This invention relates to new and useful 10 improvements in spinning tops of the general type of those disclosed in my U. S. Patent No. 1,368,039, granted February 8, 1921, and in my pending application for patent, Serial Number 422,012, filed November 5, 15 1920, which has since eventuated in Patent No. 1,428,106, under date of Sept. 5, 1922, designed to be operated by a detachable twisting head including a spring which is wound by turning the head against and in relation 20 to the body of the top.

An important object of the invention is to improve generally upon the present type of tops by producing a top body which shall consist of a few simply constructed parts 25 capable of being easily and quickly assembled, and which when assembled will provide a separate stem and spindle in direct alignment with each other and accurately positioned centrally in the top body.

30 A still further important object is to provide a top body, the upper section of which is of novel and simple construction to better retain the cap of the top in position on the body and stem.

35 A further important object is to provide means for more rigidly securing the metal stem of a top in the upper portion of the top body without extending the stem to the bottom section, and especially to provide an intermediate member above the bottom section 40 to support the inner end of the stem in addition to the two other supports of the top section and cap.

With the above and other objects in view, 45 the invention resides and consists in the construction and novel combination and arrangement of parts hereinafter to be more fully described, illustrated in the accompanying drawing, and pointed out in the claims 50 hereto appended, it being understood that various changes in the form, proportion, size and minor details of construction within the scope of the claims may be resorted to without departure from the spirit or sacrificing 55 any of the advantages of the invention.

Similar characters of reference denote like

or corresponding parts throughout the several figures of the accompanying drawing forming a part of this specification and upon which:

Fig. 1 is a perspective view of the improved form of top body showing the twisting head removed therefrom;

Fig. 2 is a central vertical sectional view 65 of the top of Fig. 1;

Fig. 3 is a view corresponding with the showing of Fig. 2, but disclosing a slightly modified form of the invention; and

Fig. 4 is a plan view of the stem supporting strip of Fig. 3.

The twisting head of the top of the invention may be of usual construction, including a shell 10, having an annular rib 11 for the better engagement of the hand of the operator, a winding spring having an ordinary 75 or preferred form of hook 12 to engage one of the holes 34 in the top body and is provided in its bottom face with notches 13 to be successively engaged by a spring actuated engaging pin 19 carried by the top body in 80 a manner presently to be fully explained.

The top body of each form of the invention includes a lower bowl shaped section 14, an upper bowl shaped section 15, a hollow sheet metal stem 16, a spindle supporting 85 member 17 preferably fastened between the lower section 14 and the upper section 15, a cap 18, a spring actuated engaging pin 19, and a spindle 20 upon which the top is adapted to spin. The spindle, as shown, is secured 90 in any desired manner to the central portion of the lower section, and the upper section is provided with an annular flange portion 21 turned in and against the annular edge portion of the lower section to fasten the sections to each other and to secure the end portions of the stem support between the edge of the lower section and the upper section.

In the form of the invention disclosed in 100 Figs. 1 and 2 the upper section 15 is made to protrude upwardly to form an annular shoulder 23 upon the top side of the upper section, the annular shoulder being adapted to snugly receive the open lower edge of the skirt 24 of said cap 18. The cap may be fastened down upon the upper section 15 in any manner, as by use of lugs 22 extending from the lower edge of the cap through holes in the top section 15 and bent against the under face of said upper section. The support 17 is 105 provided with a depression 25 receiving the lower end of the stem 16, the body of said 110

stem passing vertically upwardly through holes in the top section of the body and of the cap 18. Numeral 26 represents an annular rib upon the stem in position to be engaged by the under face of the top section, the stem in this manner evidently being rigidly supported within the upper portions of the top body and in the cap.

In the form of the invention shown in Figs. 3 and 4 the supporting member 17 is provided with a centrally arranged rib 27' provided with a concavity 25', and the lower end of the stem is provided with lugs 28 passing through openings 29 in concavity 25' and bent against the under face of the supporting member. The stem 16 of Fig. 3 likewise extends vertically upwardly and is arranged directly above the spindle 20, the body portion of this stem passing centrally through the top portion of the upper section 15 and through the body of the cap 18. The top section is defined by an annular groove 30 in which the skirt 24' of the cap seats. The cap may be secured in the groove in any manner as for instance, by means of lugs 22'. An annular rib 26' upon the stem 16 and engaging the upper face of the top section, together with the engagement of the lower end of the stem with the concavity 25', insures the position of the stem.

The spring actuated engaging pin 19 of both forms of the invention is adapted to register with the notches 13 in the bottom face of twisting head. 31 denotes a collar on the pin and 32 denotes a spring which surrounds the pin and seats against the collar and the circumferential portions 22 or 22' respectively, as the case may be to yieldably hold the pin in operating position. The opposite ends of the pin slide in holes in the cap and circumferential portion, respectively. 33 denotes a counter weight arranged in the top body and positioned on the opposite side of the stem from the spring actuated engaging pin to serve as a balance therefor. This counter weight may be a pin, as shown, or may be of any other conformation. It is preferably secured in the top section, beneath the cap, and is of a weight exactly equal to the combined weight of the engaging pin and its actuating spring so that the weight of the top body will be uniformly positioned about the stem and spindle upon which the top spins. 34 denotes holes in the body of the cap adapted to be entered by the hook 12 of the winding spring during the twisting operation of the head.

Having thus fully described the invention, what I claim as new, and desire to secure by Letters Patent is:

1. A top body comprising a lower section having a centrally arranged spindle, an upper section, a supporting member having its opposite edges fastened between said sec-

tions, and a stem, the body portion of which is fitted in a centrally arranged hole in the upper section and the lower end of which is associated with the supporting member, said stem being arranged directly above and in alignment with said spindle. 70

2. A top body consisting of a lower section having a centrally arranged spindle, an upper section having an annular flange around the marginal edge of the lower section, a supporting member, the opposite portions of which are fastened against the circumferential margin of the lower section and adjacent the annular flange of the upper section, a stem the lower end of which is secured to the supporting member and the body portion of which is snugly fitted within the upper section, said stem being arranged centrally of the top body to extend vertically upwardly in direct alignment with said spindle. 80

3. A top body comprising a lower bowl shaped section having a centrally arranged spindle, an upper bowl shaped section the marginal edge of which is secured to the lower section, a supporting member between said sections and having its marginal edge secured between the sections, a cap centrally arranged on the upper section, and a stem secured in said cap, in said upper section and in said supporting member and vertically arranged centrally of the top body and directly above said spindle. 90

4. A top body comprising a lower bowl shaped section having a centrally arranged spindle, an upper bowl shaped section, one of said sections having an annular flange spun about the marginal edge of the other bowl shaped section, a supporting member arranged transversely of said sections and having its marginal edges secured between the seam of the sections, a cap upon the upper section, and a stem arranged centrally in said cap, said upper section and said supporting member. 100

5. A top body comprising a lower bowl shaped section having a centrally arranged spindle, an upper bowl shaped section having an annular edge secured to the edge of the lower section, a cap secured centrally upon the upper section of the top body, a support secured in and to the top section and a stem arranged centrally in the body upon the support and extending vertically upward through holes in said top body and cap and directly above and in alignment with said spindle. 110

6. A top body comprising a lower bowl shaped section having a centrally arranged spindle, a supporting strip upon the marginal edge of said lower section and having a depression, an upper bowl shaped section secured to the lower bowl shaped section and fastening the edges of the supporting strip between said sections, the depression 120

sion in said strip being centrally arranged, and a stem arranged in said depression and extending vertically upward through the upper section in direct alignment with said

5 spindle.

7. A top body comprising a lower bowl shaped section having a centrally arranged spindle, a supporting strip extending transversely across said lower section and having its opposite ends resting upon the marginal edge of said section, an upper bowl shaped section having an annular flange spun about said lower section and supporting strip, whereby said supporting strip 10 provides a support between said sections, an annular shoulder extending upwardly

from said upper section, a cap having a skirt snugly fitted upon said annular shoulder, and a stem centrally arranged in said body to be in direct alignment with said spindle, said stem having its lower end supported in a depression in said strip and its body portion snugly fitted in holes in said cap and upper bowl shaped section.

Signed at Bridgeport, in the county of Fairfield and State of Connecticut, this 19th day of January, A. D., 1922.

FRANK L. LINDSTROM.
